PROTECTIVE SLEEVE FOR CHILDREN

Harry Bresnick and Esther S. Bresnick,
New York, N. Y.

Application January 19, 1940, Serial No. 314,728

1 Claim. (Cl. 128—133)

This invention relates to a protective sleeve for children which is particularly suitable for arresting harmful habits, such as finger sucking, nail biting, and the like.

It is the object of the invention to provide a protective sleeve having capabilities of variation of the restraining influence exercised thereby to the bending of the arm at the elbow which is effective not only for infants, but for children of older years, and even adults.

It is a further object of the present invention to provide a protective sleeve for children which is simple and light in construction, economical to produce, and easy to wash and keep clean.

Furthermore, the invention comprehends a protective sleeve which may be attached quickly and conveniently to the arm of a child, which is retained in position under all circumstances, and which can be easily disengaged by anyone but the wearer conveniently and with dispatch.

The invention proceeds upon the principle of a sleeve formed by a sheet of flexible material which is designed to surround the arm of the wearer above and below the elbow. Reinforcements in the form of stays of suitable material of predetermined rigidity, extend longitudinally of the sleeve and provide impediments to the bending of the arm at the elbow without interfering with the movements of the hand or arm in an extended direction. The stays may be of different material, such as Celluloid, metal, wood and the like, having different bending characteristics, and may be interchangeable in the sleeve to adjust the same to the desired purposes. A feature of the invention is the provision of one or more straps on the inside of the sleeve, one of which is designed to be fastened about the arm and preferably around the wrist of the wearer for the purpose of maintaining the sleeve in place. Although one strap at the bottom end of the sleeve has proven adequate, an additional strap may be provided at the upper end of the sleeve to be tied around the upper end of the arm. Furthermore, the sleeve is fitted with slide fastener tapes which are designed to be joined by the movement of a slide element, resulting in the rapid manipulation of the closure. A locking arrangement for the slide may be provided to prevent the movement thereof by the wearer by virtue of the fact that the locking arrangement requires either a key or the manipulation of two hands, which can only be executed by a person other than the wearer. Preferably a reinforcing slat is provided adjacent to the slide fastener in order to rigidify the sleeve at that point and to prevent the slide from being pulled

down accidentally. In order to insure against any disengagement of the holding strap on the inside of the sleeve which might be attempted by older children or adults, a flexible protuberance 5 may be fitted at the bottom end of the sleeve on the inside thereof, to minimize the space between the sleeve and the arm, to prevent access to the strap.

Other objects and purposes will appear from 10 the more detailed description of the invention following hereinafter, taken in conjunction with the accompanying drawing, wherein:

Figure 1 is a perspective view of the sleeve in 15 closed position, with parts of it broken away to illustrate the arrangement of the strap designed to embrace the wrist of the wearer;

Figure 2 is a plan view of the inside of the sleeve in open position;

Figure 3 is a front elevation of the upper end 20 of the sleeve showing in detail a different embodiment of the locking arrangement for the slide of the slide fastener from that shown in Figure 1; and

Figure 4 is a front elevation of the sleeve with 25 the lower part thereof in section showing the modification embodying a protuberance at the bottom end of the sleeve on the inside thereof.

In Figure 1 is shown a sleeve formed of a flexible material such as a textile fabric 1 having an inside backing 2 coextensive therewith and designed to be stitched at the upper and lower ends thereof, with stitching 3 and 4, respectively. Slide fastener tapes 11 and 12 are sewn on the opposite edges of the flexible sheet and the slide fastener is preferably of the type in which the same may be completely disengaged. The engagement of the tape 11 at the lowermost end thereof with a socket at the bottom end of the tape 12, permits the operation of the slide 13 in an upward direction by the movement of the handle 14 connected thereto to bring the opposite sides of the sheet in juxtaposition and to form the tubular sleeve shown in Figure 1.

45 A strap 5 is attached on the inside of the sleeve at the lower end thereof, as by stitching 6, which strap is designed to be placed around the wrist of the wearer by the engagement of the free end 8 within the buckle 7. The buckle 7 preferably 50 is of the type which requires its turning over in order to permit a disengagement of the free end of the strap, and thereby a mere tugging of the strap will not effect an opening thereof. Provision of this strap at the wrist is adequate to maintain the sleeve in position, but if desired,

another one may be provided at the upper end of the sleeve.

Following the engagement of the slide fastener, at which time the slide 13 and its handle 14 are in the positions shown in Figures 1 and 3, the same are locked in such positions by locking devices which require the manipulation of two hands to effect a release thereof. In Figure 1 is shown a flexible chain 30, attached to the sleeve and embodying a link 31 as part thereof, which chain is continuous and which may be broken at the link 31 by disengaging one end of the chain therefrom. Such chains are commonly used for different purposes, for example, for key rings. In Figure 3 a different form of locking means is shown by a ring 16, common in jewelry, which is sewn to the sleeve at 17, and which has a spring-pressed retractable segment 18 permitting the engagement of the ring 16 with the handle 14 through the opening 15. Two hands are required to hold the handle 14 and manipulate the retractile segment 18 to permit a release of the handle from the ring preparatory to a downward sliding movement of the slide 13.

The sleeve is provided with reenforcing stays extending longitudinally thereof and distributed at different points therearound. In the illustrated embodiment of the invention, four of such stays are shown at 21, 22, 23 and 24, which may be inserted in pockets 26 sewn on the inside of the sheet 1. These stays are interchangeable by ripping some of the seams permitting the removal thereof, and insertion of others. These stays may result in a rigid or semi-rigid sleeve. For the use of infants, considerable flexibility can be permitted by the use of corset boning of Celluloid inserted in three or less of the pockets 26. For children two to five years of age, a stiffer steel slat may be used permitting slight flexibility. For other children, at least one slat or stay should be almost rigid. Preferably the slat 24 adjacent to the slat fastener is substantially rigid

in order to prevent a flexing of the slide fastener and an undesired movement of the sliding element.

In order to preclude any attempt of the wearer 5 to manipulate the holding strap 5 in the buckle 1, a flexible protuberance 40 (Figure 4) may be provided at the bottom end of the sleeve on the inside thereof, which may be in the form of a half-inch cording or rubber stripping, to narrow 10 the space between the sleeve and the wrist. Thereby access to the holding band is prevented.

Various changes in the constructional embodiments of the invention illustrated herein may be made. For example, the sleeve may be independent 15 as shown, or form part of a garment. Likewise, the buckles and other fasteners may assume different forms from that illustrated herein, and accordingly, while we have described our invention as embodied in concrete form and as operating 20 in a specific manner for purposes of illustration, it should be understood that we do not limit our invention thereto, since various modifications will suggest themselves to those skilled in the art without departing from the spirit 25 of the invention, the scope of which is set forth in the annexed claim.

What we claim is:

In a device of the class described, a flexible sheet of material provided with separable slide 30 fastener elements upon opposite edges thereof adapted to form a sleeve surrounding the arm of a wearer above and below the elbow, reenforcements extending longitudinally of the sheet above and below the elbow and impeding the 35 bending of the arm at the elbow, an inelastic strap attached on the inside of said flexible sheet and set inwardly of the distal edge of the sleeve; the inside measurement of the sleeve proximate to the hand being less than the inside measurement 40 of the sleeve at the forearm.

HARRY BRESNICK.
